US00D868798S

(12) **United States Design Patent** (10) Patent No.: **US D868,798 S**
 Theodore et al. (45) Date of Patent: ** Dec. 3, 2019

(54) **DISPLAY SCREEN WITH GRAPHICAL USER INTERFACE**(71) Applicant: **Adobe Inc.**, San Jose, CA (US)(72) Inventors: **Brian Theodore**, Los Altos, CA (US);
James Dibble, Kensington, CA (US);
Elisha J. Fitch-Cook, East Lansing, MI (US)(73) Assignee: **Adobe Inc.**, San Jose, CA (US)(***) Term: **15 Years**(21) Appl. No.: **29/615,324**(22) Filed: **Aug. 28, 2017****Related U.S. Application Data**

(63) Continuation of application No. 29/560,202, filed on Apr. 4, 2016, now abandoned.

Primary Examiner — Cathron C Brooks*Assistant Examiner* — Ian F Whitmore(74) *Attorney, Agent, or Firm* — Keller Jolley Preece(57) **CLAIM**

The ornamental design for a display screen with graphical user interface, as shown and described.

DESCRIPTION

The sole FIGURE is a front view of a display screen with graphical user interface.

The outermost broken line perimeter illustrates a display screen and forms no part of the claimed design. The remaining broken lines illustrate portions of a graphical user interface and form no part of the claimed design.

1 Claim, 1 Drawing Sheet(56)
